UNITED STATES PATENT OFFICE.

THOMAS E. KNAUSS, OF COLUMBUS, OHIO.

ROUTE-INDICATOR.

SPECIFICATION forming part of Letters Patent No. 774,255, dated November 8, 1904.

Application filed October 12, 1903. Serial No. 176,678. (No model.)

To all whom it may concern:

Be it known that I, THOMAS E. KNAUSS, a citizen of the United States, residing at Columbus, in the county of Franklin and State of 5 Ohio, have invented a certain new and useful Improvement in Route-Indicators, of which the following is a specification:

My invention relates to the improvement of route-indicators which are adapted for use 10 by drivers of delivery-wagons; and the objects of my invention are to provide an improved device of this character having means whereby the various stops or calls may be plainly indicated, thereby obviating any tendency 15 on the part of the driver to miss customers or stopping-places, and to produce certain improvements in details of construction and arrangement of parts, which will be more fully pointed out hereinafter. These 20 objects I accomplish in the manner illustrated in the accompanying drawings, in which—

Figure 1 is a perspective view of my improved device, and Fig. 2 is a central longitudinal section of the same with a portion of 25 the address-cards removed.

Similar numerals refer to similar parts throughout both views.

In carrying out my invention I employ a rectangular case or box 1, having its upper 30 side open. Extending centrally through one end of said box or case and terminating at the opposite end thereof is a removable tubular rod 2, which is provided on its outer end with a suitable finger-piece or head 3. Ex- 35 tending into this tubular rod 2 through an opening in the other end of the box is a rod 4. Upon the tubular rod 2 and within the box I string or mount a plurality of cards or tickets 5, said rod 2 piercing said cards or tickets 40 at their inner ends and preferably midway of their height. Upon the cards 5 are printed or written the names and addresses of the customers, the same being arranged with reference to the order in which the stops are to be 45 made. It will be understood that the said cards may be of any desired or well-known material or construction. The cards 5 are designed to be of two distinct colors or shades, each alternate card being of corresponding 50 color or shade, and assuming, for example,

that the shades adopted are white and red each of the white cards has one of its corners cut away, as indicated at 5^a, while the adjacent red cards are suitably recessed at points out of alinement with the cut-away portions 55 5^a of the white cards, these red-card recesses being indicated at 5^b. It will thus be understood that the cut-away portions 5^a and 5^b of the cards will result in disclosing the color of the adjacent cards. 60

Assuming that the route-indicating device is to be used by the driver of a milk or other route wagon, it will be understood that the cards 5 are arranged horizontally in a single row upon the bottom of the box, the greater portions 65 of the bodies of said cards being on one side of the central rod 2. When the first stop has been made, the first card on the rod, which bears the name and address of the customer, is swung upward and over into the opposite 70 portion of the box, with its lower edge resting on the bottom of the latter. This reversal of the position of the card discloses the name and address of the next customer on the second card, and when the next customer is 75 served this second card is, as prescribed for the first card, thrown to the reversed position. In a like manner the cards are successively thrown to the opposite side of the box or case from that which they originally occupied, a 80 portion of said cards being thus shown in Fig. 1 of the drawings. Owing to the fact that the adjacent cards are distinguished by different colors and the further fact that the cards may be viewed through the breaks or 85 recesses 5^a 5^b of the adjoining cards, any tendency of the operator to turn two cards at a time through mistake is obviated. In case it is desired to insert a new card bearing the name of a new customer in its proper place 90 among the cards contained in the case it will be seen that the rods 2 and 4 may be drawn outward and separated at the proper point for the insertion of said new card and that those cards which are thus drawn off the tubu- 95 lar rod 2 will not be displaced, inasmuch as the inner rod 4 will serve to support the same until the rods are again telescoped one within the other.

It will be seen that my improved device is 100

simple of construction and that by its use failure of the driver of a delivery-wagon or other vehicle to make the required number of stops through forgetfulness may be over-
5 come.

Having now fully described my invention, what I claim, and desire to secure by Letters Patent, is—

1. In a route-indicator, the combination
10 with a case, of a tubular rod extending centrally within said case and through one end thereof and a rod extending through the opposite end of the case and telescoping within said tubular rod, of a plurality of cards having their end portions mounted to turn on
15

said tubular rod, the adjoining cards being of different colors substantially as specified.

2. In a route-indicator, the combination with a case, and a rod running therethrough and detachable therefrom, of a plurality of 20 cards having their corresponding ends mounted to turn on said rod, the adjoining cards being of different colors or shades and each of said cards having a cut-away or recessed portion through which the color of the adjoining 25 card may be viewed, substantially as specified.

THOMAS E. KNAUSS.
